HULL SPRAY REDUCING CONSTRUCTION

Walter S. Dichl, United States Navy

Application January 22, 1938, Serial No. 186,326

6 Claims. (CL 114—66.5)

(Granted under the act of March 3, 1883, as
amended April 30, 1928; 370 O. G. 757)

This invention relates to a hull spray reducing construction and has for an object to provide a structure which may be applied to flying boat hulls, hydroplane or seaplane floats, for the purpose of reducing the spray normally kicked up by the hull and causing such spray to bear rearwardly and downwardly away from the hull and away from the wing or tail surfaces when the hull is part of an aircraft.

10 A further object of this invention is to provide a spray reducing construction which may be applied to hulls according to the individual needs thereof for this purpose.

15 A still further object of this invention is to provide a spray reducing construction consisting of a plurality of steps which may be angularly applied to the outer edges of the bottom of the V of the hull.

20 With the foregoing and other objects in view, the invention consists in the construction, combination and arrangement of parts hereinafter described and illustrated in the drawing, in which,

Fig. 1 is a side elevational view of the hull to which this invention has been applied;

25 Fig. 2 is a bottom plan view of Fig. 1;

Fig. 3 is an enlarged fragmentary view of the invention; and

Fig. 4 is a sectional view on line 4—4 of Fig. 1.

There is shown at 10 a hull of the planing 30 type, and may be either a hydroplane hull or a flying boat or seaplane hull. This hull 10 has the usual keel line 11 separating the sides 12 and 13 of the V bottom of the forward part of the hull, which, in turn, is separated by the conventional step 14 from the after portion 15 of the bottom.

35 In order to reduce the spray normally present in use of the conventional hull over a water surface, a plurality of steps 16 comprising this invention are placed along the edges of the V bottoms 12 and 13, preferably in such a manner that the vertical sides or bases 17 of the steps are in the same vertical plane with the side 18 of the hull. These steps 16 are placed at an angle approximately from 45 to 60 degrees longitudinally of the hull. The rear face 19 of the step 16 is preferably vertical, while the forward surface 20 is smoothly curved or flared forwardly to merge tangentially with the bottom surfaces 12 and 13. These tetrahedral steps 16 may be 45 spaced from each other as desired, according to the characteristics of the hull. If desired, they may be spaced so closely that the forward edge of the flared surface 20 of one step may end just back of the vertical face 19 of the step next forward thereto, or they may be spaced apart as

shown, or further so according to the number of steps found desirable on a particular size of hull to effect the desired result of eliminating the spray from going forward and upward of the hull, and instead, causing it to beat rearwardly and downwardly of the hull, thereby eliminating the corrosion and the resistance normally caused by the spray striking the under wing or tail surfaces when the hull is part of an aircraft.

5 In operation, the steps 16 may be applied in 10 any desired manner. They may be either an integral part of the hull with their side 17 forming an integral extension of the side 18 of the hull, or they may be separate, individual steps, each of which is integrally secured to the particular 15 hull at the desired proper angle by riveting, bolting or otherwise fastening it thereto.

Other modifications and changes in the 20 portions and arrangements of the parts may be made by those skilled in the art without departing from the nature of the invention, within the scope of what is hereinafter claimed.

The invention described herein may be manufactured and used by or for the Government of the United States of America for governmental 25 purposes without the payment of any royalties thereon or therefor.

Having thus set forth and disclosed the nature of this invention, what is claimed is:

1. A hull spray reducing construction comprising a plurality of steps placed along the outer under edges of the bottom of the hull, said steps each being in the form of a tetrahedron having its apex forward of its base and having its base side coinciding with the chine of the hull.

30 2. A step construction for application to a hull to reduce the spray, said step construction being applied in a series along the outer edges of the bottom of the hull, said step construction being in the form of a tetrahedron.

35 3. A step construction for application to a hull to reduce the spray, said step construction being applied in a series along the outer edges of the bottom of the hull, said step construction being in the form of a tetrahedron, said tetrahedron having one curved surface, said curved surface being adapted to extend forwardly and merge tangentially with the bottom of the hull to which it is applied.

40 4. A step construction for application to a hull to reduce the spray, said step construction being applied in a series along the outer edges of the bottom of the hull, said step construction being in the form of a tetrahedron, said tetrahedron having one curved surface, said curved surface 45 being adapted to extend forwardly and merge tangentially with the bottom of the hull to which it is applied.

being adapted to extend forwardly and merge tangentially with the bottom of the hull to which it is applied, a rear surface adapted to extend vertically to the hull to which it is applied, a base 5 surface whose plane is adapted to coincide with the plane of the side of the hull, and a top surface adapted to be placed against the bottom of the hull, the plane of the vertical rear surface from the base to its apex being at an angle of from approximately 45 to 60 degrees to the longitudinal direction of the hull.

10 5. A hull spray reducing construction comprising a plurality of steps located along the outer portion of the hull bottom, said steps each being

in the form of a tetrahedron having its apex forward of its base and having its base side coinciding with the chine of the hull, the forward side of the tetrahedron curving in a smooth merger to the hull bottom.

6. A hull spray reducing step, said step being in the form of a tetrahedron, one side face of the tetrahedron being adapted to be attached to a hull bottom with the base of the tetrahedron coincident with the hull side and the apex of the tetrahedron lying between the hull chine and the hull keel and forward of the tetrahedron base.
